(57) **CLAIM**

The ornamental design for a pipe clamp as shown and described.

DESCRIPTION

FIG. 1 is a first side perspective view of a pipe clamp; FIG. 2 is a second side perspective view of the pipe clamp of FIG. 1;

FIG. 3 is a front view of the pipe clamp of FIG. 1;

FIG. 4 is a back view of the pipe clamp of FIG. 1;

FIG. 5 is a top view of the pipe clamp of FIG. 1;

FIG. 6 is a bottom view of the pipe clamp of FIG. 1;

FIG. 7 is a first side view of the pipe clamp of FIG. 1; and, FIG. 8 is a second side view of the pipe clamp of FIG. 1. The broken lines in the drawings depict portions of the pipe clamp that form no part of the claimed design.

1 Claim, 8 Drawing Sheets
